UNITED STATES PATENT OFFICE.

ULYSSES S. PAGE AND JULIUS C. PAGE, OF FALL RIVER, MASSACHUSETTS.

DESIGN FOR A LAMP.

Application filed November 9, 1923. Serial No. 7,725. Term of patent 3½ years.

To all whom it may concern:

Be it known that we, ULYSSES S. PAGE and JULIUS C. PAGE, both citizens of the United States, and residents of Fall River, in the county of Bristol and State of Massachusetts, have invented a new, original, and ornamental Design for a Lamp, of which the following is a specification, reference being had to the accompanying drawing, forming part thereof, in which—

Figure 1 is a perspective view of a lamp showing our new design, and

Figure 2 is a view thereof in front elevation.

We claim—

The ornamental design for a lamp as shown.

ULYSSES S. PAGE.
JULIUS C. PAGE.
